UNITED STATES PATENT OFFICE.

JOHN JACKSON, OF FOREST LODGE, NEAR SYDNEY, NEW SOUTH WALES, AUSTRALIA.

CASE-NAILING MACHINE.

Application filed October 23, 1923. Serial No. 670,316.

To all whom it may concern:

Be it known that I, JOHN JACKSON, a subject of the King of Great Britain, residing at Forest Lodge, near Sydney, in the State of New South Wales, Commonwealth of Australia, have invented new and useful Improvements in Case-Nailing Machines, of which the following is a specification.

This invention relates to an improved case nailing machine, and it has been devised particularly in order to provide improved means of a simple character whereby a series of nails can be driven into the assembled case parts simultaneously and in a horizontal position.

The invention also embodies an improved cleating device which is designed as an attachment to the case nailing machine whereby the necessary cleats for a case can be readily nailed in position and the nails clinched.

The primary objects of this invention are to provide a case nailing and cleating machine of simple and economic construction, which will be found particularly adaptable for the production of a rapid output in repetition work, and means providing dimensional or other adjustments as is necessary for cleating and nailing various sizes of cases.

A case nailing machine according to one embodiment of the invention is characterized by having a substantial cast metal frame, work holders adjustably mounted upon said frame, nail feeding devices adjustably supported upon said frame and adapted to deliver the nails horizontally and at predetermined intervals to nail holders arranged adjacent to each corner of the case, horizontally disposed nail punches to which is imparted a horizontal reciprocating action to drive the whole of the nails into the case simultaneously at one operation, and means for slightly raising the nail points and for guiding same in such manner as to ensure that each nail is forced by its punch in a truly horizontal plane.

Reference being had to the accompanying drawings:—

Figure 1 is a view in plan of a machine constructed according to the invention.

Figure 2 is a view in end elevation of the machine with the work holders, nail feeding and nailing devices removed.

Figure 3 is a side elevation of Figure 2.

Figure 4 is a fragmentary view in sec-

tional elevation illustrating the mechanism for operating the nail punches located at each end of the machine.

Figure 5 is a view in rear elevation of one of the nail punch carriers.

Figure 6 is a view in side elevation of one half of a punch carrier and illustrating the means whereby one set of nail punches is adjustably mounted in position thereon.

Figure 7 is a view in end elevation, on an enlarged scale, of a nail punch.

Figure 8 is a sectional view in plan taken on lines A—A of Figure 5.

Figure 9 is a view in side elevation of one of the nail supply hoppers, and a set of spiral and telescopic chutes employed to deliver nails therefrom to a series forming a set of nail holders.

Figure 10 is a central vertical section of a nail supply hopper.

Figure 11 is a detail view in plan of one of the telescopic chutes.

Figure 12 is a view in side elevation, partly in section, of one of the telescopic chutes and a nail holder associated therewith.

Figure 13 is a view in side elevation of one of the pillars which forms part of a work holder.

Figure 14 is a front elevation of Figure 13.

Figure 15 is a plan of Figure 13.

Figure 16 is a view in plan of the cleating device.

Figure 17 is a view in side elevation of Figure 16.

Figure 18 is a view in detail illustrating the position of the cleating bars when clinching a nail.

Figure 19 is a fragmentary view in elevation of a slidable cleating bar.

Figure 20 is a view in front elevation of one of the pedestals supporting a series of nail holders.

Figure 21 is a side elevation of Figure 20.

Figure 22 is an enlarged sectional view in plan taken on line B—B of Figure 20.

Figure 23 is a central longitudinal section of one of the nail holders.

Figure 24 is a central longitudinal section of an adjustable nail holder.

Figure 25 is a plan view of Figure 24.

Figure 26 is a view showing in front elevation and in edge view one of the slotted plates for controlling the delivery of nails, one at a time, to a nail holder.

Figure 27 is a view in plan of an adjust-

able bracket for supporting the nail-holder pedestals.

Figure 28 is a detail view of mechanism for operating the nail delivery plates seen in Figure 26.

Figure 29 is a view in side elevation of the mechanism for effecting the return stroke of the nail punch carriers.

Figure 30 is an end elevation of Figure 10 29.

Figure 31 is a view in side elevation of a metal strap forming portion of the mechanism illustrated in Figures 29 and 30.

In these views, the numeral 1 designates 15 longitudinally disposed main castings, which are rigidly secured together transversely and at a predetermined distance apart by suitable castings 2 in order to provide a substantial and somewhat rectangular- 20 shaped base or support, upon which is mounted the whole of the operative and other integers of the machine.

A transversely arranged rectangular-shaped bearer bar 3 is fixedly secured at its 25 opposite ends to the upper surface of the main castings 1 and inverted T-shaped slots or grooves 4 are formed in said bearer bar to slidably receive the heads of bolts 5 which enable carrier plates 6 to be adjust- 30 ably secured transversely across the bearer bar 3 so as to support adjustable work 35 holders 7. For this purpose, each carrier plate 6 is furnished with a pair of inverted T-shaped slots 8 to receive the head of the securing bolts 9 of said adjustable work holders 7.

The slotted bearer bar 3 and carrier plates 6 enable the position of the work-holders 7 to be readily adjusted longitudinally and 40 transversely to suit varying sizes of assembled case parts which are to be nailed together when mounted upon the bearer bar 3.

The work-holders 7, which are four in 45 number, are arranged at required positions to firmly grip the four corners of the assembled case parts as illustrated in Figure 1, and these work holders comprise vertical standards 10 having a base 11 adapted to 50 be secured to the carrier plate 6 by the bolts 9.

Spring actuated buffer plates 12 are fitted 55 in a vertical position to standards 10 and they are arranged at right angles to one another in such a manner as to bear against the interior surfaces of the longitudinal members A and transverse members B respectively of the case parts. These buffer plates 12 are fixedly secured to horizontal 60 rods 13 passing through holes 14 formed through the standards 10 and having screw-threaded ends, that are furnished with nuts 15 for adjusting the position of the buffer plates 12 and functioning also for the regulation of the tension of coiled springs 16

which encircle the rods 13 between said buffer plates and said standards 10. The springs 16, while exerting sufficient pressure upon the buffer plates 12 to maintain the case members A and B firmly in a relative 70 vertical position for nailing, enable case parts of varying thickness to be readily clamped in position.

The longitudinal members A of the case integers are so arranged and assembled that 75 their exterior surfaces adjacent the ends bear against the sides of a series of nail-holders 17, while the exterior surfaces of the transverse members B of said case bear against spring-actuated buffer plates 18, 80 which are mounted upon adjustable rods 19 fitted in bracket or frames 20 supporting said nail-holders.

The nail-holders 17 consist of a series of 85 downwardly inclined and superimposed trays or chutes, which are adjustably fitted in dovetail-shaped guide grooves 21 that are formed in the sides of said brackets or frames 20, and they are adapted to be locked at any selected position within said brackets or frames by a clamping plate 22, which is fixedly secured thereto by screws or studs 23.

Each nail-holder 17 is furnished at its forward end with a V-shaped channel or 90 recess 24 that receives a nail and supports the same in horizontal position, while a longitudinal guide groove 25 is formed in the upper inclined surface of the nail-holder to accommodate the head of the nail, thus permitting such nail to descend the inclined surface of the nail holder with a rolling motion into said V-shaped recess 24.

The rear portion of each nail-holder 17 is supported within the bracket or frame 20, and it is furnished with a horizontally disposed T-shaped slot 26, through which the 105 nails are delivered, one at a time from a main supply hopper 27 in the manner hereinafter described.

Each bracket or frame 20 supporting a 110 series of nail-holders 17 is furnished with a foot 28, and is adjustably mounted upon a base or carrier 29 by means of bolts 30, the heads of which engage a longitudinal slot 31 of inverted T-shaped formed in said base and enabling said bracket to be adjusted to suit the length of the cases being nailed. Each base member 29 supports a pair of said brackets or frames 20 at each 115 end of the machine, and it is secured adjustably to the upper surface of the end castings 2 of the machine frame by means of studs or bolts 32 that are passed through slots 33 formed in said base, thus permitting the position of the base members 29 and the nail-holders 17 to be adjusted as may be required to suit the width of the cases that are to be nailed.

All of the nails required to secure the assembled case integers are driven simul- 130

taneously by a series of horizontally disposed reciprocating nail punches 34, which are arranged one above the other and disposed approximately in alignment with the 5 V-shaped channels or recesses 24 formed in the upper surface of the nail-holders 17.

Each series of nail punches 34 is rigidly but adjustably mounted in carriers or holders 35 constructed of cast-metal in two sections 10 in order that said punches can be readily and conveniently removed and adjusted in position (Figures 5, 6, 7 and 8).

As is illustrated particularly by Figure 7, each nail-punch 34 has its striking end 15 formed of triangular shape in cross-section so as to pass freely along the V-shaped channel or recess 24 in the nail-holder 17 and force the nail therefrom into the assembled case members A and B.

20 The rear end portion of each nail punch 34 is screw-threaded and is screwed through a tapped block 36, which is detachably and adjustably mounted in a recess 37 that is formed by the flanges 38 of the opposing 25 sections of the punch-holder 35. The screw-threaded end of each punch 34 passes between the flanges 38, and through a square washer 39 located at the rear of said flanges, and it is fitted with a nut 40, which when 30 tightened against said washer 38, rigidly clamps the nail-punch 34 and also functions to lock together the two sections of the punch-holder.

Each nail-punch holder 35 is rigidly, but 35 adjustably, mounted upon a bearer bar 41 (Figures 1 and 2), for which purpose a dovetail groove 42 is formed on the rear surface of each half of the holder. This groove 40 slidably accommodates the similarly shaped upper and lower edges 43 of said bearer bar 41, and said holder can be locked at any required adjusted position along said bearer bar by clamping plates 44 and studs 45, thus 45 permitting adjustments being made so as to suit cases of variable dimensions required to be nailed.

Brackets 46 are formed integrally with the bearer-bar 41, and they are fixedly, but adjustably, secured to pedestals 49 by means 50 of bolts 47 passing through slots 48 formed in said brackets, the pedestals being secured to, or formed on, a transversely disposed reciprocating carrier 50. (Figures 2, 3 and 4.) This carrier is slidably mounted in a guide 55 51, carried by the upper portion of the longitudinal main casting 1 of the machine frame.

A pair of carriers 50 is arranged at each end of the machine, and the inner end portions of opposing carriers overlap. If desired, 60 the inner end portions of one pair of carriers at one side of the machine may be bifurcated to receive the inner end of the opposing carriers.

Fixedly secured to the inner end portion 65 of each carrier 50 is a pivot pin 52 having

its ends passing freely through a slot 53 that is formed in the rear end portion of the opposing carrier, and the projecting ends of said pivot pin are supported in bearings 54 which are slidably mounted in guide-ways 55 formed in the upper end portions of the side members 1 of the machine frame.

A downwardly and inwardly inclined link 56 is pivotally attached at its upper end to each pivot pin 52, the free and lower ends of 75 said links being pivotally mounted on a shaft 57 extending transversely of the framework. This shaft is rotatably mounted in bearings 58 slidably mounted to have vertical reciprocatory movement in guides 59 formed in the side frames 1, rollers 60 fixed on said shaft at a required distance apart frictionally engaging suitably shaped cams 61, which are mounted eccentrically upon another transverse shaft 62. The link connection 80 of the carrier 50 with the shaft 57 is in the nature of a toggle connection and as the shaft 57 is vertically reciprocated by the cams 61 the carriers 50 and thereby the nail punch carriers will be moved in a direction 85 toward and away from each other. This shaft 62 is disposed below the roller shafts 57, and is rotatably mounted in stationary 90 bearings 63 secured to or formed on the side members 1 of the machine frame.

95 Rotary motion is imparted to the cam-shaft 62 by a train of toothed wheels 64, to which motion is transmitted by a pinion 65 keyed on a main driving shaft 66. This driving shaft is revolvably mounted in bearings secured to the machine frame, and it is furnished with a driving pulley 67 to receive a power transmission belt (not shown) from an electric motor or other source of 100 motive power.

105 When rotary motion is transmitted to the cam-shaft 62, the engagement of the cams 61 with the rollers 60 on the shaft 57 causes a combined rotary and vertical reciprocating motion to be imparted to said roller shaft 57. Simultaneously, the pivotal link connection 56 between said roller shaft 57 and the carriers 50 (supporting the nail punch holder 35 at opposite ends of the machine) 110 causes required horizontal reciprocating motion to be imparted to the nail punches, whereby all of the nails that are supported upon the nail-holders 17 are driven at one 115 operation into the assembled case integers.

120 In order to positively ensure the return movement of the reciprocating carriers 50 and roller shaft 57 at the end of each operative stroke in nailing operations, an eccentric 68 (Figures 29, 30 and 31) having the same throw as the eccentric cams 61 is keyed upon the cam-shaft 62 at a position about the centre of its length, and a metal strap or band 69 is passed loosely about said eccentric 68. This strap also passes about and is secured by a stud 70 to a roller 71 loosely 130

mounted upon said roller shaft 57. This metal strap functions to maintain the rollers 60 in constant frictional engagement with the cams 61 and provides for an even reciprocating motion being imparted to said carriers 50 and to the nail punches 34 and holders 35 supporting the latter.

The nails for securing together the assembled case parts A and B are deposited 10 in the nail hoppers or receptacles 27, each of which is partitioned into a series of vertically arranged narrow compartments 72 (Figures 1 and 10) having sloping bottoms 73 furnished with discharge slots 74, through 15 which the the nails project with their points depending downwardly through said compartments. Each nail hopper 27 is revolvably mounted by means of brackets 75 on a transverse spindle 76. This spindle is 20 fixedly supported at its opposite ends in apertured bosses 77 that are formed at the upper ends of brackets 78, which are affixed at their lower ends to the machine frame, as is illustrated in Figure 9 of the drawings.

25 A tipping motion is imparted to the nail-hoppers 27 by means of a lever 79, which is pivotally mounted upon said spindle 76. This lever 79 has one end pivotally attached by a link 80 to a lug or bracket 81 depending from the rear portion of the nail hopper 27, while the opposite end of said lever is pivotally attached by a rod 82 to a lever 83, secured on the outer end of a rocking bar 84. Said rocking bar 84 is revolvably 30 mounted in bracket bearings 85 secured to the machine frame, and it is furnished with a lever 86 pivotally engaging a pin 87 secured to and projecting from the pedestal 49 supporting the nail punch-holders 35.

40 The reciprocating movement of the carriers 50 supporting the pedestals, on which are mounted punch-holders 35 imparts intermittent tipping motion simultaneously to the nail hoppers 27 by reason of the pivotal 45 connection of the same with the punch-holders 35. The intermittent tipping motion thus imparted to said nail hoppers causes the nails in each of the compartments to be discharged therefrom gravitationally in a vertical position into a slotted and inclined chute or tray 88, which (Figure 9) is rigidly supported by brackets 89 that are secured to the supporting brackets 78. This inclined and slotted chute or tray

50 55 60 65 70 75 80 85 90 95 100 105 110 115 120 125 130 has its slots registering with the upper and vertically disposed ends of a series of spiral chutes 90 so as to deliver the nails by gravity into said chute. The spiral formation of the chutes ensures delivery of the nails in a horizontal position one behind the other into a series of telescopic chutes or trays 91 each having its movable element 92 hingedly or pivotally attached at 93 to the delivery end of a spiral chute 90, while the stationary element is secured to the rear end

of a nail-holder 17 at its undersurface by a bracket 91^a, as is illustrated particularly in Figure 12. The discharge end of the stationary element of each of the telescopic chutes or trays 91 is positioned slightly above 70 the T-shaped slot 26 formed in the rear portion or wall of a nail-holder, and vertically slidable between the discharge end of the stationary element of the telescopic chute and the rear portion of the nail-holder is a 75 cut-off plate 94, having a horizontal T-shaped slot 95 of required dimensions to snugly accommodate the head and the shank of a nail.

Each cut-off plate 94 is fixedly but adjustably mounted in a frame 96, which is vertically slidable in the rear portion of the bracket or frame member 20 supporting a series of the nail-holders 17.

Vertical reciprocating motion is transmitted to the slidable frame 96, supporting the cut-off plates 94, by means of a bell-crank lever 97 pivoted upon a pin or stud 98 secured to the bracket or frame member 20 (Figure 28). One arm of said bell-crank 90 lever has a slot 99 to receive a pin 100 secured to the lower transverse member of the slidable frame 96, while the other arm of said bell-crank lever is fitted with a pin 101, which passes through a slot 102 formed in 95 the end of a push rod 103 that is affixed to the nail punch holder.

Reciprocating movement of the nail punch holder 35 by reason of its pivotal connection with the vertical slidable frame 96 supporting the cut-off plates 94 causes a vertical reciprocating movement to be transmitted to one series of said cut-off plates, whereby at the termination of the upward stroke of said plates, a nail gravitates from the discharge 100 end of each telescopic chute 91 into a slot 95 in a cut-off plate 94. At the termination of the downward stroke of said cut-off plate the slotted portion of the same is brought into register with the guide slot 26 formed 105 in the rear portion of the nail-holder 17, thus enabling the nails to be delivered by gravity one at a time through said guide slot.

Each nail after passing through the slot 26 in the rear portion of the nail-holder 17 110 115 120 125 130 gravitates by a rolling motion down the inclined surface of said holder, until it is held in a horizontal position in the V-shaped channel or recess 24 formed therein.

The reciprocating movement of the carrier arms 50 causes each nail puncher 34 to contact with the head of a nail supported in the V-shaped channel 24 and drive the same in a longitudinal direction into each corner of the assembled case integers.

The drawings show an arrangement wherein six nail punches and six nail holders are provided for driving six nails simultaneously into each corner portion of the assembled case parts, but it will be readily

understood that any required number of nail holders and punches can be arranged at required distances apart for driving a selected number of nails into a case, according to the dimensions thereof.

In order to enable cleats to be nailed to the case parts, and the points of the nails clinched, I provide cleating devices as illustrated in Figures 16, 17, 18 and 19 for attachment to the machine. These cleating devices comprise two vertically disposed hollow metal castings 104 of rectangular configuration, which are adapted to take the place of the work-holders 7 when the cleating operation is being performed. Said metal castings are fixedly but adjustably mounted upon the carrier plates 6, which for this purpose have recesses 105 formed on the underside of their opposing edges to accommodate therein a clamping plate 106.

A rib or flange 107 is formed integrally on and depends from the bottom of each of the castings 104 and is adapted to fit snugly within the space 108 formed between the opposing edges of the said carrier plates 6, while a bolt 109 having its head countersunk into the clamping plate 106 passes upwardly through a hole 106^a formed in the bottom of the casting 104 and is fitted with a nut 110 for rigidly securing said casting in position.

Furnished in each of the said castings 104 on opposite sides thereof is a vertically disposed dovetail guide 111, which slidably accommodates a reciprocating slide 112 having integrally formed on the outer surface thereof three transverse horizontal bars 113 which extend across the side of the said casting 104 and have their lower edges 114 chamfered.

Two vertical distance bars 115 disposed one on either side of said slide 112 have on their interior surface three lugs 116 the upper edges 117 of which are chamfered to correspond with the chamfers 114. These lugs 116 are adapted to register and contact with the bars 113 which impart simultaneously with the forward movement of the nail punches a horizontal reciprocating motion to said vertical distance bars 115, which are guided during this motion by means of two horizontal guide pins 118 secured to and projecting from the inner surface of said distance bars, being slidably accommodated in guide holes 119 that are formed in the side of said casting 104.

A vertical clinching plate 120 is snugly disposed between the opposing edges of the pair of distance bars 115, and it is secured at its upper and lower ends by countersunk screws 121 to lugs 122 formed integrally with and projecting from the slide 112.

The vertical slides 112 that are slidably

accommodated in the dovetail guides 111 formed in the opposite sides of each of the main castings 104 are rigidly connected together by a bridge-bar 123 which is furnished with a centrally disposed apertured boss 124, through which is passed a horizontal spindle 125, the projecting ends of which are adapted to reciprocate in vertical slots 126 formed in each end of the wall of the casting 104.

Connecting rods 127 are pivotally connected at their upper ends to the horizontal spindle 125, and the lower end of each connecting rod 127 is secured to the upper end of the rod 128 of an eccentric 129 which is mounted upon the cam shaft 62.

Rotary motion being transmitted to the cam shaft 62 causes the eccentric 129 to impart a vertical reciprocating motion to the said slides 112, which are initially at the lower end of their stroke at the commencement of the cleating operations. By this arrangement the vertical distance bars 115 will be in advance of the clinching plate 120 for the purpose of forming a space 130 between said clinching plate and the case member B as seen in Figure 16. The spaces 130 provide ample room to enable the ends of the nails to be driven through the cleats C and case member B by the advancing nail punches 34 without danger of being bent in such action.

At the predetermined moment when the shank of the nail has been passed through the cleat and case member and the head thereof is flush with the former, the slides 112 move the transverse wedge shaped bars 113 to disengage from the lugs 116 formed on the vertical distance bars 115 allowing the said bars 115 under the advancing pressure of the said nail punches to retrieve flush with the clinching plate 120—see Figure 18. The upward moving clinching plate 120 now engages with the end of the nails and clinches and inlays same into the case member B.

It is necessary that cleats should be nailed to the case integers B before the same are assembled in the machine with the case parts B for nailing. For this purpose, the work-holders 7 employed to maintain the case integers in position for nailing are removed, and the case integers and the cleats are secured firmly in position between the vertical distance bars 115 and the slides of the nail-holder 17 while the nails are driven in the manner hereinbefore described.

What I do claim is:—

1. In a case nailing machine, the combination with the machine frame, of brackets carrying nail holders in superposed relation, a series of work holders to engage assembled case members adjacent the corners to position the same relative to the nail holders, each of said holders comprising

- brackets mounted on adjustable carriers supported on the machine frame, rods adjustably mounted in said brackets, buffer plates mounted on said rods, and springs 5 encircling said rods and interposed between said brackets and buffer plates, substantially as described.
2. In a case nailing machine, a nail holder consisting of a tray having an inclined 10 supporting surface and at its forward end a channel of V-shape in longitudinal section, a guide groove at one side of said tray, and said tray having an entrance slot of T-shape formed at its opposite end, said 15 slot and said groove being so arranged that a nail will roll down the inclined surface of the tray into said V-shaped channel, substantially as described.
3. In a case nailing machine, the combination with the machine frame, of vertically extending brackets supported by the machine frame to have adjustment toward and away from each other; and a series of superimposed nail holders adjustably mounted 25 on each of said brackets, each of said nail holders having a transversely extending V-shaped nail holding channel at its forward end, a T-shaped slotted portion at its opposite end, and a guide groove at one of its 30 side portions intermediate the V-shaped channel and slotted portion.
4. In a case nailing machine, a hopper arranged with a series of compartments, a series of nail holders each having a T-shaped slot formed therein, chutes to receive nails from the hopper compartments and deliver said nails into said nail holders, cut off plates located between the discharge 35 ends of said chutes and the entrance ends of said nail holders, each of said cut off plates having a T-shaped opening corresponding to the T-shaped slot of the holders and adapted to be alternately brought into register with the end of a chute and the correspondingly shaped slot in a nail holder to deliver nails from the chute to the nail 40 holder.
5. In a case nailing machine, a frame, nail 45 holders carried by the frame in superposed and predetermined spaced relation, means to position assembled case sides and ends 55 relative to the nail holders, nail punches, carriers in which said punches are mounted relative to the nail holders, means to actuate said punch carriers, comprising a horizontal roller shaft mounted in said frame to have 60 vertical sliding movement, oppositely arranged carriers for the punch carriers mounted in said frame for transversely sliding movement and having their inner ends overlapping, pivotal link connections between said carriers and roller shaft, a cam shaft, a cam on said shaft operative to impart vertical upward movement to said roller shaft, and means for effecting downward movement of said roller shaft substantially as described.
6. In a case nailing machine, the combination with the machine frame, of brackets mounted thereon, nail holders mounted in said brackets in spaced relation, carriers 75 in which said nail holder carrying brackets are mounted in opposed pairs, said carriers being mounted upon the machine frame to have adjustment toward and away from each other, and the brackets of each pair of 80 brackets having adjustment in said carriers toward and away from each other, means to position and clamp case sides to the nail holders mounted in a bracket of each pair of brackets and to position case ends in interposed relation to the case sides and clamp said ends to each pair of nail holder brackets, carriers upon which said clamping means is adjustably mounted and said carriers having adjustment with the clamping means 85 relative to and away from each other, and nail punches reciprocable transversely of the nail holders and toward and away from the case sides clamped to the nail holders to drive nails carried by the nail holders into 90 the case sides and interposed case ends to secure the two together.
- In testimony whereof I affix my signature in the presence of two witnesses.

JOHN JACKSON.
